UNITED STATES PATENT OFFICE.

HARRY SLIKERMAN, OF BROOKLYN, NEW YORK, ASSIGNOR TO THE BELFIT BRASSIERE COMPANY, INC., OF BROOKLYN, NEW YORK, A CORPORATION OF NEW YORK.

BRASSIERE CORSET.

Application filed October 7, 1921. Serial No. 506,017.

To all whom it may concern:

Be it known that I, HARRY SLIKERMAN, a citizen of Russia, residing at Brooklyn, in the county of Kings and State of New York, have invented certain new and useful improvements in Brassière Corsets, of which the following is a specification.

This invention relates to wearing apparel for women, an object thereof being to provide an improved brassière and corset combined in a single continuous one-piece garment, the brassière portion thereof being so constructed as to perform all of the functions of a bust supporter or brassière, but also the functions and purposes of a camisole.

A further object of this invention is to provide a brassière garment having a bust supporting portion, and adjustable hip portions, adjustable only from the waist to the lower edge.

A further object of this invention is to provide an improved brassière and corset which will be so formed with continuous gores or panels non-separable around the entire waist as to preclude any relative movement of the parts and the consequent discomfort to the wearer resulting from friction against the body, as for instance, when moving or bending over, such being the case in garments heretofore constructed with the brassière and corset either partially or wholly detached or separable adjacent to the waist.

A further object of this invention is to provide a one-piece brassière undergarment for women, the garment being non-detachable or non-separable around the entire waist or adjacent to the waist and having the back thereof solid or closed to the waist, and also having back and hip portions adjustable from the waist to the lower edge. The brassière is provided adjacent to the front thereof with an opening, and preferably releasable concealed connections from the top of the garment to the lower edge thereof. As a result of this construction, the brassière portion of the combined garment may be so formed of suitable fancy material with the back portion thereof continuous or solid to the waist and without lacings or openings and the front portion

provided with concealed fastenings, that it may serve not only as a brassière but also as a camisole, thereby combining in a single garment a corset, brassière, and camisole.

A further object of this invention is to provide a brassière-corset having a bust supporting portion and also having means, such as reinforcing strips, connecting certain of the hose supporting members with the shoulder straps of the garment such that the strain or pull upon the hose supporting members will be transmitted directly to the shoulder straps, thereby permitting the stress or strain or support of the hose supporting members to be borne directly by the shoulders of the wearer. As a result of this construction, the tendency of the garment to sag or wrinkle at any point is eliminated and the consequent discomfort to the wearer incident thereto avoided. Furthermore, by having a direct line of stress from the shoulder straps through the garment to the hose supporting members, all of the parts of the garment will be more positively and firmly held in their proper positions with respect to the body. The tendency to form wrinkles will be done away with, and hence greater comfort and more satisfactory results accorded the wearer.

Other objects of this invention will appear in the following description thereof, reference being had to the accompanying drawing forming a part of this specification, wherein like reference characters indicate corresponding parts in the several views, and wherein Fig. 1 is a perspective view of my improved garment; Fig. 2 is a rear view thereof; Fig. 3 is a perspective view illustrating a garment spread out; Fig. 4 is a fragmentary view illustrating the upper portion of the garment; Figs. 5 and 6 are detail perspective views of the concealed fastenings for the garment; Fig. 7 is a detail sectional view thereof; Fig. 8 is a section on line $\alpha-\alpha$ Fig. 3; and Fig. 9 is a front perspective view illustrating a modified form of my invention.

Referring to the drawing, wherein I have illustrated a preferred embodiment of my invention, it will be seen that the garment is constructed with a plurality of continuous panels or gores suitably connected to

gether so as to form a one-piece integral garment. The panels or gores may be cut to any suitable length so as to extend to the desired point below the hips and above or adjacent to the bust. As herein shown in Figs. 1 to 4, the garment comprises continuous lengthwise extending front panels or gores 9, side gores or panels 10, and rear panels 11, 12 and 14. It will be seen that the panels 9, 10 and 11 are secured together in any suitable manner and the same extend continuously the entire length of the garment. The back or rear panels 12 in the present instance are secured to the panels 11 at either side thereof, and preferably extend to points substantially midway of the back or adjacent to the waist line, and are secured as at 13 to panel 14 also stitched to the lengthwise extending panels or gores 11. In this embodiment of my invention the garment at the front thereof is provided with an opening 15 from the upper to the lower edge thereof. The adjacent panels 9 are detachably or releasably connected together, preferably by means of concealed fastenings 16 and 17 as illustrated in Figs. 4 to 7 inclusive. The adjacent panels 12 at the rear of the garment are provided with an opening 18 therebetween extending to a point adjacent to the waist and the same are flexibly interconnected by means of lacings 19 or any other form of adjustable connection. Thus, the lower portion of the garment, which is constructed to form the corset, may be adjusted as desired to fit the wearer by means of the flexible connections 19. It will be further noted that the upper portion of the garment, which is constructed to form a brassière or bust supporter, has no opening at any part of the back thereof, which constitutes a very important and advantageous feature, as hereinafter pointed out.

The continuous or integral panels forming this improved one-piece garment may be provided in any preferred manner with stays or stiffening means, the same in the present instance, comprising stays 20 inserted in tubular openings 21 formed at the seams of the adjacent gores or panels, as particularly illustrated in Figs. 3 and 8.

Thus, in order that the combined one-piece brassière and corset may be provided with the necessary stiffening means, the stays will preferably extend substantially or approximately the entire length of the garment.

In the embodiment illustrated in Fig. 9, the construction of the garment is substantially the same as that in the embodiment hereinbefore described with the exception that the opening at the front of the garment is dispensed with and in lieu thereof the garment is provided with an opening 22 and detachable or releasable connections 23 adjacent to the side thereof. In such case, the

front panels 9 will preferably be stitched together as at 24, but in all other respects, particularly as regards the novel construction of the back, the garment will be the same as hereinbefore described.

Adjacent to the lower edge thereof, the front panels or gores 9 are provided with the usual front hose supporting members 25. At the back of the garment suitable hose supporting members 25^a are also provided, the same being connected to the gores 11 and 12, preferably at the terminal juncture point thereof, as shown at 26 in Figs. 2 and 3. The usual or customary shoulder straps 27 are secured to the brassière portion of the garment, in the present instance, the same being connected to the front reinforced seams 28 and the back reinforced seams 29. From the relation of these parts therefore, it will be readily seen that the rear hose supporting members 25^a and the shoulder straps 27 are connected at the opposite ends of the continuous lengthwise extending reinforced seams 29, thus having a direct line of stress through the garment, whereby the strain or pull from the hose supporting members will be transferred and taken up by the shoulder straps.

It will be particularly noted that the brassière portion of this garment has a substantially permanent fit or shape to the waist line, and that the garment is also provided with an adjustable hip portion permanently joined to the brassière-corset, the hip portion being quickly and effectively adjusted at the back by suitable adjustable means. Hence, with the solid or closed back to the waist line and thereby substantially a permanent shape or fit, it is possible to draw in and adjust the hip portion more effectively, easily and more nearly in accordance with the lines of the figure. This effective hip adjustment is possible in the present invention by drawing the hip portion together by a simple downward pull of the lacings extending to the lower edge of the back as particularly shown in Fig. 2, and insures maximum comfort and proper fit due to the fact that it is possible to draw in the hip portions without drawing in the waist. Hence the hip portions only may be adjusted to the form without applying substantial pressure at or above the waist line.

Furthermore, as a result of this structure, whereby the shoulder straps 27,—which may be of elastic or somewhat resilient material,—are at all times subjected to stress or tension, the tendency of the brassière portion to wrinkle or bunch together either in the front or back thereof will be entirely eliminated.

Therefore, it will be readily perceived that the desirability of this combined brassière and corset as affording maximum comfort, will be materially enhanced.

On account of the fact that the brassière portion of the garment is so constructed as to form a continuous or solid garment throughout the back thereof to the waist without lacings or openings, the same may therefore be constructed to supplant or take the place of a camisole, serving at the same time as a brassière. For this purpose, as stated, the back of the brassière portion is continuous or solid; the material is made preferably of silk or silk finish or the like, and the upper edge thereof is provided with lace or ribbon as desired. Thus, in essence, I have provided a single continuous one-piece garment combining three functions, namely, that of a corset, that of a brassière and that of a camisole. The brassière portion is suitably stiffened, so as to perform the functions thereof, and at the same time is constructed at the front and the back as well, as in regard to material and finish to perform the functions of a camisole.

As will be inferred from the above description the garment above the waistline is continuous, except for the releasable fastening means used to secure the garment in place on the body of the wearer. There are no laces or other means for positively adjusting the girth of the garment above the waist.

Furthermore, it will be readily observed that I have provided a single continuous garment without any transverse opening around or adjacent to the waist, and wherein maximum comfort may be accorded the wearer by virtue of eliminating entirely the tendency of the garment to wrinkle or cause friction.

Although I have described my invention in its preferred form, it is to be understood that I do not limit myself to the construction herein shown and described, but may make any and all changes embraced within the scope of the appended claims.

I claim as my invention:

1. A brassière corset garment including an integral structure extending above and below the waist so as to embrace the bust and the hips, said garment having releasable fastening means at one side thereof, the top edge of said garment being substantially straight and terminating below the line of the armpits, the back of said garment being solid or uninterrupted from the top down to the waist line and the part of said garment above the waist being solid or non-adjustable, said garment at the rear side being bifurcated from the lower end to the waist line only, and means for adjusting and drawing in said garment at the back from the lower end to the waist line only.

2. A brassière corset garment including an integral structure extending above and below the waist so as to embrace the bust and the hips, said garment having releasable fastening means down one side thereof, said garment being solid or non-adjustable above the waist line and being bifurcated at one side from the waist line down to the lower edge, and means for adjusting or drawing in said garment from the waist line only to the lower edge without disturbing the fit of the garment above the waist.

3. A brassière corset garment comprising an integral structure extending above and below the waist so as to embrace the bust and the hips, said garment above the waist line being continuous except for releasable fastening means down one side thereof, said garment at one side being bifurcated from the lower end to the waist line only and being adjustable from the lower end to the waist line only whereby the hip portion may be drawn in or adjusted without disturbing the fit of the garment above the waist.

Signed at Brooklyn, New York, this 28th day of September, 1921.

HARRY SLIKERMAN.
